Emory Osgood

UNITED STATES PATENT OFFICE.

ENOCH OSGOOD, OF BROOKLYN, NEW YORK.

PUMP.

SPECIFICATION forming part of Letters Patent No. 258,250, dated May 23, 1882.

Application filed May 14, 1881. (No model.)

To all whom it may concern:

Be it known that I, ENOCH OSGOOD, a citizen of the United States, residing at No. 1 Mid-dagh street, Brooklyn, in the county of Kings and State of New York, have invented certain new and useful Improvements in a Three-Part (more or less) Automatic Conical - Valved Pump; and I do hereby declare the following to be a full, clear, and exact description of the invention, such as will enable others skilled in the art to which it appertains to make and use the same, reference being had to the accompanying drawings, and to the letters or figures of reference marked thereon, which form a part of this specification.

My invention relates primarily to pumps, though it is applicable in other situations for forcing water for the propulsion of ships, canal-boats, and the like, as well as for elevating 20 water or for throwing it in streams.

It consists in devices and combinations hereinafter fully set forth and specifically claimed.

Heretofore in apparatus used for forcing water or for drawing and lifting it one special 25 difficulty to be overcome has been that of keeping the water constantly in motion, in order to avoid the shock of the valves or other lifting parts against the solid column of water when at rest. To obviate this and kindred difficulties many devices have been tried and used, 30 all of which are well known to those skilled in the art.

In my improved apparatus I have succeeded 35 in giving to a column of water a continuous movement without any sudden impulse or shock to the valves or to any part of the apparatus, and without the necessity of using any check-valves. This apparatus is represented in the accompanying drawings, in which—

40 Figure 1 shows a central longitudinal section of the fixed and movable parts of the tube or cylinder, with the operating mechanism and the valve in side elevation. Fig. 2 shows an additional construction in which my invention 45 is carried forward in its application to other situations, as hereinafter fully explained.

In the drawings the fixed sections of the tubular construction are shown at A A. As 50 represented, they are four in number, and are attached to any suitable support by ears B B, through which pass suitable screws or bolts.

Upon the ends of these fixed sections, which are in line with each other, are placed corresponding tubular sections, C C, having annular screw-caps *a* over the threaded ends of 55 tubes C and intermediate packing, *b*. These parts are so arranged as to permit the same amount of motion to all the movable parts C. As shown, these parts are three in number; but in practice two or more may be used. I 60 have shown the connections B B only upon the upper and lower fixed sections; but it will be understood that the intermediate sections are connected firmly to a base or standard in like manner. It will be observed that the 65 movable parts are the larger and work on the outside of the fixed parts, the fixed parts being plain cylindrical tubes.

Within the movable parts C, midway of their length, I place valves D D, hinged opposite 70 each other and adapted to close upon the annular valve-seat *f*, the inner periphery of which is of the same diameter as the tubes A. The valves D D are formed out of sections of tubular material, of metal, in any suitable manner. 75 These sections are made, as shown in the figures, so that when placed upon the seat, as shown in the upper section of Fig. 1, they form a practical conical figure, or, more exactly, being in the shape of two tubes cut to meet at 80 right angles. The vertical faces of these sections meet and fit accurately when the valves are placed upon their side. They are hinged so as to act automatically in the current of water, as is hereinafter fully described. It will 85 be understood that when these valves are open they lie against the wall of the tubular part, in which they are pivoted; but as their shape corresponds in contour to that of the wall of the tube and their thickness does not exceed 90 that of the fixed part, when open they do not in any degree obstruct the flow of the water. Their peculiar action in connection with the special construction and operation of the movable sections will be referred to hereinafter. 95 The movable sections are connected to a shaft, O, by means of cranks E and links F. These cranks are set upon the shaft at different angles, and the arrangement of these cranks is such as to advance and retract the sections 100 successively, so that their position at one point in the revolution of the shaft O would be as

shown in Fig. 1, where the upper valves are closed, the middle half open, and the lower quite open, in which position the upper pair of valves would be in action, forcing the water, 5 the last in full return and the intermediate in an intermediate position.

Obviously for the operation of this apparatus two pairs of valves would be sufficient, 10 acting alternately. The result of this construction is that a continuous stream of water is forced through the tube, and by the successive action of the valves there is no shock whatever upon any of them, for while one valve is forcing and drawing upon the water 15 the second valve, having reached the limit of its motion, and thereby beginning to move more slowly than the stream itself, opens with a gradual movement, and is then drawn back with the valves lying against the walls of the 20 tubular section. As they reach the limit of their backward movement the continuous revolution of the shaft arrests each section and causes it gradually again to advance as the shaft carries the arm past the dead-center. 25 The motion of the section in this revolution of the crank-arm, being little slower at first, gradually overtakes the current of water, and by pressure against it closes the valves, but at the same time closes them by a gradual press- 30 ure, which pressure increases as the forward motion of the section increases, and the same action is followed by all the sections and their valves in succession. The valves are so hung as to move inward when relieved of the pressure of a current of water moving past them, 35 so that they close automatically by their own weight, or with no other pressure than that afforded by the stream of water against which they move. It will be observed, therefore, 40 that this form of valve is specially adapted to the special construction of the pump. The valve moves only through one-eighth of a circle. It is adapted also to the larger and smaller sections, so that it leaves the larger tube un- 45 obstructed and a passage-way through it equal in diameter to that of the fixed sections A. Manifestly the valves D might be hinged in the sections A, but with less favorable results. It will be readily understood that other means 50 may be used in the place of the shaft O, with its cranks and connecting-rods F. I have shown these as being well adapted to the valves, it being necessary only that the section should reciprocate in proper order, so that the 55 valves of one section should take hold of the column of water at the proper instant when the valves of the other sections are opening or moving back in a fully opened position. The column of water is never arrested in its motion with this proper arrangement of the movable sections, and there is no shock to any of the moving parts of the mechanism.

I have described the device as specially applicable to pumps for forcing or raising water; 60 but it is also applicable for the propulsion of ships or canal-boats.

For the propulsion of ships or any kind of water-craft the tubular structure may be located in the bottom, by the side of the keelson; or one may be used upon each side of the keelson. It will be understood that the tube in such a case should extend the entire length of the ship and be provided with an opening through the ship, both at the bow and stern, so that the water could be drawn in at the bow and 70 forced out at the stern. The special advantages which arise out of this mode of propulsion need not be herein fully described. The principle is that the water is drawn in from about the bows and heaped up at the stern, 75 reversing the position of the water as it impedes the progress of the vessel in sailing. For use in canal-boats its location at the greatest depth of the craft renders it particularly applicable, since it can be used without any 80 disturbance of the water, which occasions the washing of the banks. For use upon water-craft it may be duplicated in the manner shown in Fig. 2, and be provided with double catches, so that the moving tube represented in said 85 figure may be made to operate in either of two directions. The valves D D are pivoted upon opposite sides of the valve-seat f, and are provided with catches I I, pivoted in lugs and on the outside of the tube-section, and connected 90 by an arm, H, so that both valves may be thrown into gear with the valves D when open on one side, while the valves on the other side of the valve-seat are left free to operate.

In order to reverse the apparatus, and thereby the direction of the current and the movement of the ship, it is only necessary to change the position of the catches.

A device of this sort for propelling ships does not interfere with the sailing qualities of 105 the ship.

I am aware that a moving section has been heretofore described carrying a valve and acting like a plunger, as in the patent of Tapley, No. 11,704, September 19, 1854; and I am also 110 aware of the form of valve shown in the patent of Dodge, No. 9,706, May 10, 1853, and I desire to have my claims understood as limited in view of what is shown in said patents.

Having thus described my invention, what 115 I claim is—

1. A device for forcing water, consisting of the fixed and movable sections and devices for operating the movable sections, in combination with the double valves D D and valve-seats, the sections being adapted to operate successively, substantially as described.

2. The combination of the fixed inner sections, A, the outer movable sections, C, and the valves D D, hinged in said outer sections, 125 whereby when said valves are open they do not obstruct the flow of water, all substantially as described.

3. The combination of the fixed and movable sections and the valves with the crank-shaft cranks set at different points on the shaft, 130 and connecting-rods connecting cranks to the

movable sections, whereby said sections are operated successively, substantially as described.

4. The double-acting valves D D, arranged in pairs on opposite sides of the seat, and combined with the alternately-operating catches, substantially as described.

5. The combination of two or more movable sections of a pump with fixed sections and with two or more sets of valves, said movable sections sliding upon said fixed sections, and

being provided with mechanism, substantially as described, for moving them successively in proper order, all as set forth.

In testimony whereof I affix my signature in presence of two witnesses.

ENOCH OSGOOD.
